WITNESS:

Gerald Hennessy

UNITED STATES PATENT OFFICE.

LEO B. PAULSON, OF SAN DIEGO, CALIFORNIA.

HINGE.

Application filed February 27, 1926. Serial No. 91,152.

This invention relates to improvements in hinges for especial adaption for screen doors and the like and which permits ingress and egress from a doorway from either side of the door.

Another object of the invention resides in the peculiar construction of the hinged means which allows the door to be held firmly and pivoted at either side of the door 10 and which will swing all the way open as in the usual and ordinary type of single hinges.

With the above and other objects in view, the invention further includes the following novel features and details of construction, 15 to be hereinafter more fully described, illustrated in the accompanying drawing and pointed out in the appended claim.

In the drawings:

Figure 1 is a perspective of a door frame 20 and showing the hinged means connected therewith and further illustrating the manner in which a door may be swung open at either side.

Figure 2 is a horizontal section taken 25 through a portion of the door frame and door when in a closed position and showing the relative arrangement of the hinges thereon.

Figure 3 is a perspective of the upper portions of the door frame and door and showing the door partly open.

Figure 4 is a plan view of the hinged members and plate member therefor.

Figure 5 is a sectional view of the lower 35 end of the door and a portion of a sill and showing the arrangement of the hinged members upon the front side of the sill when the door is in a closed position.

Figure 6 is a perspective of a second modification of my invention.

Figure 7 is a transverse section through 40 a closed door with the second modification applied.

Referring to the drawings in detail, 45 wherein like characters of reference denote corresponding parts, the reference character 10 indicates the usual and ordinary type of door frame and 11 the stoop or sill which is also of the usual and well known construction and includes a bevelled portion 12 upon the inner side thereof which is inclined 50 toward the floor of the house while the opposite and outer side of the sill or stoop 11 which is exposed to the weather is substantially flat as illustrated at 13; it is of

course obvious that some sort of door is to be used upon this door frame 10 and stoop or sill 11 and in the showing of my invention I employ a usual and ordinary type of screen door 14.

My invention resides in the provision of a plate member 15 which includes a substantially inwardly offset portion 16 upon one side thereof and which is adapted to be secured to the outer side and adjacent the ends of the door 14 at the bottom and top. Each of these plates 15 have hingedly secured as at 17 upon both ends thereof and in spaced relation thereon, end portions of hinged plates 18; 65 the opposite ends of these hinged plates 18 include hinges 19 upon the opposite free end portions thereof and which are adapted to be secured to the upper and lower ends of the door frame 10. Arranged centrally 70 of the width of the upper portion of the door frame 10 and stoop or sill 11 are braces 20 and 21 respectively which are adapted to receive and engage the lower sides of the hinged plates 18 thereon and support the 75 same when the door is swung open and also in its closed position in order that the screen door 14 will be held against sagging in order that the hinges 19 will not be pulled or in any way disengaged from the door 80 frame 10. It is of course obvious that these hinges 19 may include such spring means 85 therein, not shown, which will be tensioned in directly opposite directions in order that the door will be closed automatically when 90 opened in either direction.

In the mode of operation of the invention it is manifest that owing to the relative association of the spring hinges 19 to the upper end of the door frame 10 and outer flat 95 side 13 of the stoop or sill 11 and the relative association of the hinge arms 18 with the spring hinges 19 and the opposite ends of the plates 15 with their supporting means of the braces 20 and 21 respectively, it will 100 be noted and manifest that this screen door 14 may be pushed or pulled upon either side when going "in" or "out" of a doorway and swing in such position as the occupant may desire for egress and ingress through the 105 doorway.

In Figures 6 and 7, I have illustrated a second modification of my invention which is quite similar to the preferred and first modification, including every element of the 110

combination as shown but which also shows such slight departures and arrangements as will be hereinafter more fully described.

This form of my invention contemplates the provision of channelled braces 13^a having apertured lug members 14^a and 15^a extending outwardly from the upper and lower portion of the braces 13^a and upon the opposite ends thereof. These braces are 5 obviously mounted upon the upper and lower edges of the door frame 10 while the door 12 in turn is adapted to fit wholly within the door frame 10 in the manner illustrated in Figure 7.

10 15 Mounted in reverse order upon the upper and lower edges of the door 12 are plate members 18^a having offset apertured lug members 19^a provided on one of their ends while downwardly extending portions 20^a are provided adjacent the opposite ends of 20 the plate members 18^a which terminate in outwardly extending plate members 21^a which extend outwardly and below the level of the lug members 19^a. In order to facilitate the operation of this modification as 25 described, I provide pairs of companion hinge plates 22^a and 23^a respectively; the hinge plates 22^a have their respective ends terminating in outwardly extending apertured lug members which have their opposite ends pivoted to the lug members 14^a and 19^a respectively, while the ends of the hinged plates 23^a are correspondingly constructed and secured to the lug members 15^a and outwardly extending plate members 21^a. It is 30 thus noted that when using this form of my invention that the door 12 is arranged wholly within the door frame 10 and that the same may be opened from either side 35 and upon the opposite sides thereof.

40 It will thus be noted from the foregoing description and accompanying drawings that this modified form of my invention will also operate in the same manner as the preferred form, that is, to facilitate the open-

ing of the door 12 from either side in order that the ingress and egress of persons through a doorway and the like will be facilitated to such an extent that it will make no difference what side of the door is opened and if used in the instance upon doorways in business houses will reduce the traffic congestion through the doorways when using this novel form of device.

50 It is also to be noted that this invention provides a very useful and efficient device for use upon screen doors and screens for use in windows as well as doors to be used in business houses which are frequently inconvenient for egress and ingress of patrons.

55 The invention is susceptible of various changes in its form, proportions and minor details of construction and the right is herein reserved to make such changes as properly fall within the scope of the appended 60 claim.

65 The invention, owing to the construction thereof may be equally and effectually as well applied upon the doors of motor vehicle bodies and which will overcome the usual difficulty in the opening of the doors when articles are carried upon the running boards therefor or the particular occupant of the vehicle forgets at which side or end the door is hinged.

70 Having thus described the invention, what is claimed is:

75 A hinge construction comprising plate members carried upon the ends of the door, hinged plates pivotally connected in staggered relation to the ends of the plate members, hinges carried upon the remaining ends of the hinged plates and connected with the door frame, and braces carried by the door frame and disposed between the hinged plates to alternately support companion hinged plates when the door is opened from either side to prevent sagging of the door.

80 85 In testimony whereof I affix my signature.

LEO B. PAULSON.
